DAMPER ASSEMBLY

Eugene R. Cooper, Asheville, N. C.

Application March 30, 1953, Serial No. 345,313

3 Claims. (Cl. 98—41)

This invention relates to air distributing systems and more particularly to an automatic damper assembly for use in such systems.

In many air circulation systems, it is common practice to introduce the heated or cooled air into a room through an opening in the overhead or ceiling. This opening is usually connected to a duct horizontally mounted above the ceiling and carrying air to a series of rooms. Usually a diffuser of some type is mounted in the ceiling opening so that the blast of air issuing into the room will not be felt by a person directly beneath the opening. Such diffusers are available in a wide variety of sizes and designs and are well known in the art.

Heretofore no provision has been made for automatically controlling the amount of air entering each room through such a ceiling opening or diffuser. Most diffuser units used in ceiling openings are provided with a manual adjustment for controlling the flow of air through the unit, but such manual adjustment is necessarily difficult and unsatisfactory in view of the remote location of the unit and since it requires frequent adjustment. The present invention is concerned with a method for eliminating these difficulties.

This invention comprises a damper assembly which may be readily connected to a duct above a ceiling diffuser for the purpose of automatically controlling the amount of air passing from the duct through the ceiling diffuser. The damper is controlled by a thermostat mounted within the room below.

Details of the invention will be explained by reference to the accompanying drawing, wherein:

Figure 1 is a perspective of one embodiment of the invention showing the damper in closed position.

Figure 2 is a sectional view taken along the line 2—2 in Figure 1 and showing the assembly of Figure 1 mounted in an air conditioning system. In Figure 2 the damper is in open position.

Referring now to Figure 1, there is shown a base member 1 constructed of sheet metal and having mounted thereon a damper 2. The damper comprises a substantially square thin sheet of sheet metal hinged at 3 so that it may be raised to expose an opening (not shown) in base member 1 directly beneath the damper 2. Mounted on base member 1 adjacent hinge 3 is U-shaped supporting member 4. Supporting member 4 is provided with two aligned holes, one near the top of each vertical leg of supporting member 4. There is also mounted on base member 1 an electrical control motor and related reduction gear assembly 5, provided with a driven shaft 6. Shaft 6 passes through the two aligned openings in supporting member 4. Shaft 6 is biased toward connecting socket member 7 on gear assembly 5 by means of a spring 8. Spring 8 is concentrically disposed around shaft 6 and is normally held under slight compression by means of cotter key 9 and one of the upright legs of supporting member 4. The purpose of spring 8 will be discussed further below. The free end of shaft 6 is pro-

2

vided with a radial extension 10. Mounted on extension 10 is a rotatable wheel or sheave 11. A cable 12 which passes over sheave 11 is connected at 13 to damper 2 and at 14 to the base member 1, as shown. It will thus be apparent that as the shaft 6 rotates in a clockwise direction (looking toward the motor from the shaft) sheave 11 will be carried in a clockwise direction through the arc defined by the extension 10 with the result that cable 12 will be lifted and damper 2 will be opened. With the damper open, if the shaft 6 rotates an additional one-half revolution in a clockwise direction, the damper will be closed.

Electric control motor and related reduction gear assembly 5 is a standard type "electric janitor" control motor, commercially available, and is adapted to rotate shaft 6 approximately one-half of a complete revolution in response to a signal from a standard thermostat 15. Such a secondary transformer type control motor is commercially available from the Minneapolis Honeywell Corporation, Minneapolis, Minnesota, and is well known in the art of air conditioning and heating. The thermostat 15 will, of course, be mounted in the room below the damper. If necessary, a transformer 16 may be connected to supply the proper voltage to the motor and reduction gear assembly 5.

The method in which this automatic damper operates is believed to be obvious from the foregoing description. If the installation is to be used in a heating system, when the temperature in the room reaches the lower limit at which the thermostat 15 is set, the electric motor and reduction gear assembly 5 receives electric current and rotates shaft 6 in such a manner as to open damper 2. When the temperature in the room satisfies the thermostat, the motor and reduction gear assembly 5 rotates the shaft 6 an additional one-half of a revolution closing damper 2.

An important advantage of the present invention is that it provides a completely assembled damper unit ready to be attached to a duct. It will be observed in the drawing that base 1 is provided with holes 17, 18, 19, 20, etc. so that it may be readily connected to the bottom of the duct by means of sheet metal screws. The opening cut in the bottom of the duct is only large enough to accommodate that part of the base member 1 carrying the damper 2 and U-shaped supporting member 4. The motor and gear assembly 5 is, then, disposed outside the duct. This permits subsequent servicing and prevents dirt or grease from the motor being transferred to the air in the duct. The shaft 6, of course, must pass through the side of the duct in the completed assembly, and it is in this connection that the spring 8 surrounding the shaft 6 has its primary use.

The installation in a duct of the complete damper unit shown in Figure 1 is accomplished as follows: First, an opening is cut in the bottom of the duct adjacent one side thereof of sufficient size to accommodate that part of the base member carrying the damper and U-shaped supporting member. This opening is cut adjacent one side of the bottom of the duct in order that the shaft may protrude through that side of the duct and make connection with the motor and gear assembly 5 mounted outside the duct on the base member 1. Next, a small hole is cut in the side of the duct at the proper location to accommodate the shaft 6. Then, to mount the base member and its component parts on the duct, the shaft is disconnected at the motor and pressed outwardly away from the motor, compressing spring 8. With the shaft in this condition, the base member 1 is placed in position over the opening in the bottom of the duct. The damper and the U-shaped supporting member, of course, fit up inside the duct and the shaft 6, biased by the compressed spring, slides along the side of the duct until it

intercepts the hole previously prepared for it whereupon it slips through the hole and may be connected to the motor and gear assembly outside the duct through connecting socket member 7. The base member 1 is then connected to the duct by means of screws and the assembly is complete. Very satisfactory results are obtained by the use of a shaft having a hexagonal head or end in combination with a socket member having a hexagonal-shaped recess therein. The spring member, of course, tends to constantly urge the end of the shaft into the recess to provide a driving connection between the motor and the shaft.

Figure 2 shows the assembly of Figure 1 mounted on a duct with the damper in open position. The base unit 1 is connected over an opening cut in the bottom of horizontal duct 20 by means of sheet metal screws 21, 22, etc. It is seen that the damper 2, the U-shaped supporting member 4, and related parts such as the sheave 11 and cable 12 fit up inside the duct 20. Connected directly beneath the opening in the damper 2 is a conduit 23 leading to a diffuser 24 disposed adjacent ceiling 25 in the room below.

The flow of air through the duct 20, as indicated by horizontal arrows, is such that when the damper 2 is opened a portion of the air will be diverted by the damper 2 and directed via conduit 23 through diffuser 24 into the room below. When damper 2 is closed, of course, all of the air flowing through the duct 20 will by-pass conduit 23. The motor, and gear assembly, not shown in Figure 2, is located outside the duct 20 with the shaft extending through the side wall of the duct. In this location, the motor and gear assembly are accessible for servicing or repair and are completely isolated from the moving air in the duct.

The assembly illustrated and described may easily be installed either in an existing air distributing system or in a new system being built. While a single embodiment of the invention has been described, it will be apparent that various changes and modifications may be made therein without departing from the spirit of the invention.

What is claimed is:

1. In an air distributing system, an air supply duct extending horizontally above the ceiling in a room, said duct having an opening in the lower side thereof, a base member attached to the outside of said duct and provided with an opening in fluid communication with the opening in said duct, a damper connected to said base member and disposed inside said duct, an electric motor providing a source of rotary power disposed outside said duct, a thermostatic control for said motor, a shaft connected in driving relation to said motor, means responsive to the rotational movement of said shaft to cause said damper to open and close said opening in said base member, means to disconnect said shaft from said motor to permit

longitudinal movement of said shaft and resilient means urging said shaft toward said motor.

2. In an air distribution system, an air supply duct extending horizontally above the ceiling in a room, said duct having an opening in the lower side thereof, a base member attached to the outside of said duct and provided with an opening in fluid communication with the opening in said duct, a flat damper door pivotally connected to said base member and adapted to intercept a portion of the air flowing through said duct when said door is in open position, an electric motor providing a source of rotary power disposed outside said duct and attached to said base member, a shaft supporting element connected to said base member and disposed inside said duct, a rotatable shaft detachably connected to said motor and extending from said motor through the side of said duct and supported by said shaft supporting element, and means connecting said shaft to said door to cause said door to open and close in response to rotary movement by said shaft.

3. In combination, a flat metal base member having an opening therein, a flat door member pivotally connected to said base member and adapted to fit over said opening, an electric motor providing a source of rotary power mounted near the edge of said base member, a shaft supporting element connected to said base member, a rotatable shaft supported by said element and extending between said element and said motor, an arm extending normal to the axis of said shaft and connected to said shaft, a sheave connected to said arm, the axis of said sheave being substantially parallel to the axis of said shaft, resilient means urging said shaft toward said motor, means to connect said shaft to said motor for rotation thereby and means to disconnect said shaft from said motor to permit longitudinal movement of said shaft, and a flexible cable extending from said door to said base member, said cable being connected to said door and said base member and adapted to intercept a groove on said sheave whereby upon rotation of said shaft said door is opened or closed.
